WINDOW SCREEN

Application filed July 13, 1928. Serial No. 292,343.

This invention relates to improvements in the construction of window screens and more particularly to screens that are formed entirely of metal. The frame portion, to which the screen wire is secured, being of metal that is formed with an open channel portion in which the edges of the screen wire is placed. A metallic locking strip is provided which is located in the open channel portion for stretching and securing the screen wire in place, one edge of the locking strip being in engagement with and located along a bend in the screen wire. The other edge of the locking strip is formed with two folded portions which leave a substantially V-shaped part between the folds, which part engages and snaps onto the other edge of the channel in the frame member. It may, when desired, be easily removed for repairing the screen wire.

A further object is to provide means for retaining the corner portions of the channel members securely in place. This is accomplished by means of a right angular shaped piece that is formed with recesses or openings and in the recesses are located tongues that are struck up from the metal comprising the frame. A further object is to provide a window screen which may be readily shipped by parcel post in a disassembled or knocked down condition, whereby when the screen is to be assembled and installed it may readily be accomplished by an ordinary workman.

Referring to the drawings:

Fig. 1 is a detailed view of one corner of the assembled screen showing the metallic channel member and a part of the screen netting, the metallic locking strip in the channel member which operates to firmly stretch the wire fabric.

Fig. 2 is a detailed transverse sectional view of the channel member portion of the frame with the screen wire secured in place by means of the inserted strip.

Fig. 3 is a detailed sectional view on the line 3—3 of Fig. 1 illustrating the construction of the corner piece which is retained in place by the struck up tongues of the metallic frame member.

Fig. 4 is a sectional view on the line 4—4 of Fig. 3.

Fig. 5 is a detailed view of the corner.

Fig. 6 is a vertical sectional view showing the window screen in place, and illustrating the spring catch on the window sill for holding the screen down.

Fig. 7 is a front elevation view of Fig. 6 partially broken away.

Fig. 8 is a sectional view on the line 8—8 of Fig. 7 showing the U-shaped runway for the screen frame and the angular shaped strip on the window sill for holding the screen in place when it is in a lowered position.

Fig. 9 is a modification of the groove or U-shaped metal strip that is pivotally connected to the window frame, and

Fig. 10 is a modification for supporting the screen from the upper portion of the window frame for a casement window construction.

Referring to the drawings in detail:

1 designates the screen wire. 2 the channel members each of which are formed with a bottom portion 3, the upwardly extending end part 4, the horizontally extending portion 5, the end 6 of which is bent inward to form the curved surface or edge 7. 8 is a portion that is bent upward which is the inner edge of the frame and forming the angle part 9. 10 designates the locking element for securing the screen wire in place in the channeled frame members 2, and, at the same time stretching the screen wire. The edge part 11 engages the screen wire 1 at the bend 9 of the metallic frame. It is then folded as indicated at 12 on itself forming the portion 13, then folded at 14 and against the part 11. It is folded a third time as indicated at 15 and the end 16 is bent inward against the portion 13. The two folded edge parts 12 and 15 provide a V-shaped edge as indicated at 17 which engages the curved edge 7 of the frame. The locking strip 10 is inserted by placing the edge portion 11 against the screen wire 1, as shown. It is then moved inward, in the direction of the arrow 18 forcing the V-shaped edge 17 against the curved edge 7. Since the portion 5 is more

or less elastic it serves to retain the locking member 10 in place and properly stretches the screen wire 1.

The adjacent corner pieces 2 are locked together by means of the right angular shaped member 19, having the depressions 20 and 21. The members 2 are formed with struck up tongue portions 20 which enter the recesses 20' and 21 as shown in Fig. 4. Their ends engage the shoulders 23 thus preventing the adjacent corner portions of the screen frames from drawing apart.

Referring to Fig. 6 which shows the complete window frame installed, 24 designates the window sill on which the lower edge 4 of the screen frame rests. 25 is a strip of angle iron that is secured to the sill 24 by means of the screws 26. 27 is a spring catch that is located on the strip 25. It is formed with a shoulder part 28 that snaps over the portion 8 of the screen frame when the screen is moved downward. This prevents the removal of the screen from the outside of the window screen. It is to be understood that this view shows the screen as being insertable from the inside. The runway is indicated at 30. 31 is the dotted line position of the screen when it is being inserted from the inside. 32 is a folded spring for closing the opening or space at the upper edge 33 and the runway 30 for preventing flies from passing downward into the opening. The runway 30 is secured to the vertical side of the window frame 34 with the screw 35. The part 36 receives the rear edge 3 of the screen and the edge 37 of the runway receives the edge 4 of the screen. By means of this construction the edge 4 does not engage the screw 35 when the screen is moved upward or downward. 40 The flange 25' of the angle iron strip 25 holds the screen firmly in place against the part 36 of the runway and prevents the screen from being moved inward when in its lowermost position.

45 It should be stated that the spring 32 allows for any differences in distances between the width of the screen frame and the distance between the edges of the metallic runway.

50 Fig. 9 illustrates the frame of the screen in the U-shaped runway which comprises a pivotal section 38 that is secured to the window frame with the screw 39. 38' is the fixed section. When it is tipped, as shown, into the dotted line position the window screen section may be inserted from the inside. When it is inserted the screen and the runway is tipped back into the vertical or full line position, the screen may then be lowered or raised as desired in the runway. This construction permits a screen to be inserted where shelves or other obstructions would not permit the screen to be inserted the usual way.

55 In Fig. 10 is shown a tubular shaped mem-

ber secured to the under side of the upper part 40 of the window frame with the screw 41. This member is formed with the ledge part 42 and the curved edge 43. The screen in this construction is formed with a folded portion 44 which rests on the ledge 42 as shown in full lines. It is inserted in the manner indicated in the dotted line position. This construction is for casement windows and hangs, or depends, from the part 40. The construction of the window screen is exactly the same as if shown in the other with the addition of the folded part 44.

What we claim is:

1. A window screen construction comprising a wire screen securing frame having a channel shaped piece with an opening in one of its sides, a wire screen bent to enter the opening and extending into the channel portion, a screen locking strip for retaining the wire netting of the screen in place, which comprises a metallic member that is closely folded a plurality of times upon itself to form a groove-like part which engages the edge of the screen and edge of the opening respectively.

2. A window screen construction comprising a metallic member that is formed with a bottom portion and integral upwardly extending parallel side portions and an integral top portion that is spaced from one of the integral parallel side portions to form an opening to receive an edge of a screen wire, a removable locking member in the wire receiving opening comprising a metallic strip that is formed with an edge to engage the screen wire and two folded portions which form a V-shaped edge which engages the edge of the opening of the top portion of the metallic member.

3. A window screen having in combination with the screen wire, a frame having a base part with integral upwardly extending parallel inner and outer side portions, an integral inwardly extending top part that is parallel to the base part, the inwardly extending top part terminating a distance from the upwardly extending inner edge to form an entrance opening for an edge of the screen wire, a removable screen securing member that is folded three times upon itself and located in the screen entrance opening, the securing member having an edge part that engages the screen at or near one of its edges and, another part which is folded to form a V-shaped seat that rests against the edge of the said inwardly extending top part, the construction being such that the width of the screen securing member is slightly greater than the width of the screen entrance to permit the member to be sprung into the screen entrance.

4. A locking element for the purpose described comprising a strip of metal which is bent three times to form a free edge, its op-

posite edge being folded upon itself to form a V-shaped seat portion and a connecting portion between the free edge and the folded seat portion.

5. A metallic window screen frame comprising a side and an end member which is substantially tubular in cross section and having an entrance opening for an edge of the screen wire, a removable locking strip that
10 is bent three times for removably securing the screen wire and which strip which is arranged at an angle to the upper and lower portion of the tubular member, one edge engaging an edge of the screen wire and the
15 other engaging the diagonal edge of the entrance opening, said edge being elastic to provide a frictional grip on the bent locking strip.
